UNITED STATES PATENT OFFICE.

LLOYD E. SMALL, OF REYNOLDS, INDIANA.

AUTOMATIC ROAD-GUIDE.

1,192,131.

Specification of Letters Patent. Patented July 25, 1916.

Application filed November 18, 1914. Serial No. 872,840.

To all whom it may concern:

Be it known that I, LLOYD E. SMALL, a citizen of the United States, residing at Reynolds, in the county of White, State of Indiana, have invented certain new and useful Improvements in Automatic Road-Guides; and I do hereby declare the following to be a full, clear, and exact description of the invention, such as will enable others skilled in the art to which it appertains to make and use the same.

This invention relates to an automatic road guide.

An object of the invention is to provide a device of this character by means of which instructions may be automatically given to a vehicle operator during a specified trip so that instructions will be given to the operator at predetermined fractions of a mile.

20 A further object of the invention is to so construct the device that it will be automatically operated by the ordinary mileage instrument.

25 A further object of the invention is to so construct the device that a film on which instructions are printed at intervals will be maintained in view of the operator during the traversing of a predetermined distance, but which will be automatically moved to 30 expose the next instructions when the said distance has been covered.

With these and other objects in view, such as will appear as the description progresses, my invention comprises the combination and arrangement of parts as set forth in and falling within the scope of the appended claims.

Figure 1 is a front elevation of my device, showing the same operatively attached 40 to a mileage instrument. Fig. 2 is a vertical sectional view. Fig. 3 is a similar view taken on a plane at right angles to Fig. 2. Fig. 4 is a fragmental detail of the tripping mechanism. Fig. 5 is a detail of the 45 mechanism for moving the film cylinder. Fig. 6 is a detail of the film cylinder. Fig. 7 is a detail of one of the controlling cylinders. Fig. 8 is a sectional view showing the gearing for moving one of the controlling cylinders. Fig. 9 is a detail of the film, used. Fig. 10 is a detail perspective view of the tripper levers and the mounting therefor.

Referring to the drawing wherein like 55 parts are indicated by like characters throughout the several views:—Before en-

tering into a detail description of my device it may be well to here state the general operation of my device. I have provided a casing in which are mounted a plurality of 60 rolls from one to the other of which a film is rolled. This film passes over and is actuated by a cylinder so that the film is moved at predetermined intervals, for instance, after the machine has traversed one-tenth of a mile. These films are to be placed upon the rolls at the beginning of each trip and contain printed instructions for the particular trip.

The reference character 10 indicates a rectangular casing which is divided into two compartments 11 and 12, the compartment 12 having a slot 13 in the front thereof over which extends a magnifying glass 14 so that as the film passes behind this slot the glass 75 will assist in making the instructions thereon clear. On the side walls 15 and 16 of the compartment 12 are located trunnions 17 and 18. Rotatably mounted on these trunnions is a cylinder 19 which entirely encircles the trunnion 16 and is mounted in a depressed portion 20 of the trunnion 18. Extending through the cylinder 19 and the trunnions 17 and 18 and rotatably mounted therein is a shaft 21 having a squared 80 portion 22 and a round portion 23. On one end of this shaft 21 is a gear 24.

A casing 25 is provided which is attached to one end of the casing 10 and is adapted to be attached to the mileage instrument indicated generally by the reference character 26. In this casing is provided a stub shaft 27, on one end of which is a gear 28 meshing with the gear 24 on the shaft 21, while on the other end of this shaft 27 is a gear 90 29 which is arranged to mesh with the gear 30 of the mileage instrument, the latter gear actuating the indicator to turn one-tenth of a mile.

On the squared portion 22 of the shaft 21 100 is fixedly mounted a cylinder 31 which is of lesser diameter than the inner diameter of the cylinder 19, while on the rounded portion 23 of the shaft 21 is loosely mounted a cylinder 32 of similar formation to the 105 cylinder 31. Thus it will be seen that as the gear 24 is actuated the cylinder 31 will be turned therewith and in order that the cylinder 32 may be turned proportionately slower preferably in the ratio of one to ten 110 to the cylinder 31, I have provided on the end of the shaft 21 a gear 33 which meshes

with a gear 34 carried by the said cylinder 32. This gear 34 co-operates with an internal gear 35 within the cylinder 32. The relation of the gears 33, 34 and 35 is such that upon one revolution of the gear 33 the gear 35 together with the cylinder 32 will be moved one-tenth of a revolution.

Located beneath the cylinder 19 in spaced relation are two rolls 36 and 37 on one of which a film 38 is wound and on the other one the film after passing over the roll 19 is adapted to be wound. On one end of each of these rolls is a pulley 39 over which a belt 40 passes so that the rolls will be moved in synchronism in a manner to be described.

The cylinder 19 is provided with a plurality of rows of holes 41 as shown in Fig. 6 of the drawing, the said rows extending longitudinally of the cylinder and located ninety degrees apart. The cylinders 31 and 32 are each provided with a series of holes corresponding in number to the holes in each of the rows of the cylinder 19 and extending in a helical path completely around the cylinder. On the end of each of the cylinders 31 and 32 are located numbers 42 which indicate and correspond to the holes in the said cylinders, the holes adjacent the ends of the cylinders being designated by the characters one to ten as may be seen in Fig. 7 of the drawing.

Mounted on and encircling the trunnion 18 is a collar 43 which extends over the end of the cylinder 19 and has a cut-out portion 44 equal to one-fourth of the length of its circumference. A pin 45 extends outwardly from the cylinder 19 and into the said cut-out portion 44. A similar pin 46 is mounted on the collar 43 and is connected to the first mentioned pin by means of a coil spring 47; on the other end of this collar 43 is a gear 48 which extends through a slot 49 in the wall 50, which wall separates the compartments 11 and 12, and meshes with a gear 51 revolvably mounted on a stub shaft 52. This gear 51 is actuated by a spring 53. The collar 43 has four slots 54 formed therein, which slots are separated by cross bars 55. In order that the actuation of the device may be automatically controlled, I have provided a shaft 56 located in the chamber 12 above the cylinder 19. On this shaft is secured a hollow cylindrical member 57 having a plurality of cut-out portions 58 therein, which provide edges 59 on the said cylindrical member 57. These cut-out portions 58 are of a corresponding number to the holes 41 in each of the rows in the cylinder 19 and are located immediately above the members of said rows. On the shaft 56 in each of the cut-out portions 58 is loosely mounted a lever 59 which has a downwardly extending finger 60 adapted to enter the adjacent hole 41 in the cylinder 19. Secured to the upper end of these levers 59 are

springs 61 which are secured to the forward side of the rear wall of the casing 10. On the end of the shaft 56 is secured rigidly a tripping member 62 which has a cam portion 63 arranged to extend into the slots 54 in the collar 43 and to ride up over the bars 55 as will later appear.

Pivots mounted on the wall 50 between ears 64 is located a pawl 65 which has a finger 66 arranged to engage the cross bars 55 and which is resiliently connected to the member 62 by a spring pressed rod 67. In order that this pawl 65 may be maintained normally in locked position, I have provided a coil spring 68 which is connected to the tripping member 62 and extends upwardly and is connected at 69 to the top of the compartment 12. On the forward end of this member 62 is secured a rod 70 which extends upwardly through the top of the device and is connected to a lever 71 which is operable as a knocker for a bell 72, said knocker being maintained in inoperative position by a coil spring 73.

Extending through one side wall of the casing 10 is a shaft 74 having a handle on the outer end thereof and a gear 75 on the inner end thereof, which gear meshes with the gear 48 so that after the film has been used it may be rewound manually in a manner to be described.

In operation a film such as illustrated in Fig. 9 of the drawing is wound upon the roll 37, carried over the cylinder 19 and attached to the roll 36. This film as will be noted from Fig. 9 of the drawing has a plurality of holes therein which register with the holes 41 in the cylinder 19. Assuming that the film is in starting position one of the holes therein registers with one of the holes 41 in the cylinder 19 and the said hole is located adjacent the inner end of the cylinder 31 inasmuch as the holes in the film 38 are arranged in definite order with relation to the holes 41, from the left to right. At this time the spring 61 causes the finger 60 of the proper lever 59 to extend through the hole in the film through the hole in the cylinder 19 and rest upon the surface of the cylinder 31. At this time a printed instruction is visible through the slot 13 in the front of the casing. As the vehicle advances the shaft 21 is rotated and the cylinder 31 likewise rotated. When the parts are in these relative positions, the locking pawl 65 is in its locked position against one of the bars 55 and the tripping member 62 lies out of the slots 54 and the spring 47 is not extended. As the cylinder 31 rotates, the first hole from the left thereof comes beneath the hole in the cylinder 19 through which the finger 60 extends and this finger immediately drops into the said hole in the cylinder 31 and at the same time the tripping member 62 drops into one of the slots 130

54 because of the fact that the finger 60 contacts with the edge 59 of the adjacent cut-out portion 58 and the member 57, shaft 56 and tripping member 62 are thus operated against the tension of the spring 68. It is understood that the spring 61 is of greater strength than the spring 68 and thus permits this operation. At the same time the locking pawl 65 is drawn out of engagement with the bar 55. Immediately upon the finger 60 dropping into the hole in the cylinder 31 the cam 63 on the member 62 engages the next adjacent bar 55 and thus the finger 60 is withdrawn from the hole in the cylinder 31 and further withdrawn from the hole in the cylinder 19 and the film. As soon as the pawl 65 is disengaged from the bar 55, the spring 53 operates to turn the collar 43 until the said pawl 65 is pushed 20 downwardly again by the cam 63 and engages the next adjacent bar 55. At this time the film is stationary, the finger 60 still extending through the hole in the same and through the cylinder 19, the motion being 25 allowed between the cylinder 19 and the collar 43 by virtue of the resilient connection by means of the spring 47 between the same, the spring extending; and when the pin 45 reaches the end of the slot 44 in the said 30 collar 43 the action of the cam 63 in lowering the pawl 65 into the path of movement of the bars 55 raises the finger 60 out of engagement with the film and the spring 46 rotates the cylinder 19 one-fourth of a revolution, at which time the next adjacent finger 60 drops through a hole in the film and through one hole in the cylinder 19 and the 35 operation is repeated. Thus the cylinder 31 operates to turn the film over one-tenth of a 40 mile. After one mile has been covered, however, one of the fingers above the cylinder 32 operates in a similar manner inasmuch as the cylinder 32 has at this time made one-tenth of one revolution.

45 Immediately in advance of the turning of the film, that is, upon the downward movement of the cam portion 63 of the member 62, the knocker 71 is operated to strike the bell 72 so that the operator will be notified 50 of the turning of the film. It is of course to be understood that the holes in the film 38 bear a definite relation to the holes 41 in the cylinder 19 and that the holes in the cylinders 31 and 32 bear a definite relation 55 to the holes in the cylinder 19 so that the fingers 60 may drop through the holes in the film, the holes in the cylinder 19 and into the holes in the cylinders 31 and 32.

When it is desirable to rewind the film 60 after a trip has been completed the knocker 71 is gripped and pulled upwardly until the fingers 60 disengage the film, at which time the handle on the end of the shaft 74 is gripped and the film rewound upon the roll 65 37. Simultaneously with the rewinding of

this film the spring 53 is rewound and when the knocker 71 is released the device is rewound and ready for another operation. Of course I have provided the side of the casing 10 with a suitable door so that the film may 70 be taken out and replaced by a different film.

In connection with the cylinders 31 and 32, it is to be understood that the cylinder 31 makes ten revolutions to every revolution of the cylinder 32. Thus when the cylinder 31 has made a complete revolution the first finger from the left of the cylinder 32 will drop into the cylinder and maintain the same in position until the cylinder 31 again begins to operate on its second revolution at which time the finger will be withdrawn from the cylinder 32 and the operation will continue as before.

From the foregoing description it will be 85 readily seen that I have provided a road guide which will consist of an automatically operated film on which instructions to the operator are printed, and I have provided means for actuating the said film after a 90 predetermined distance has been traversed by the vehicle to which the device is attached.

While I have illustrated and described a particular embodiment of my invention, I 95 have merely done so for the sake of convenience and I do not wish to be limited to that particular embodiment as it is obvious that numerous changes may be made in the details of construction thereof without in 100 any way departing from the spirit of the invention or without exceeding the scope of the appended claims.

I claim:—

1. An automatic road guide comprising a 105 casing, a shaft rotatably mounted in said casing and adapted to be connected to a mileage instrument and rotated thereby during the advance of a vehicle, a cylinder fixedly mounted on said shaft, and a cylinder 110 rotatably mounted thereon, a cylinder rotatably mounted in the said casing and encircling the two first mentioned cylinders, a film passing over the said last mentioned cylinder and means coöperating with the 115 first mentioned cylinder to arrest the movement of the film at predetermined intervals, and means coöperating with the second mentioned cylinder to arrest the film at predetermined intervals.

2. An automatic road guide comprising a rotatably mounted cylinder, a film passing over said cylinder, and having holes therein, the said cylinder having holes registering with the holes in the said film, a plurality of cylinders rotatably mounted within and movable with relation to the first mentioned cylinder, said last mentioned cylinders having holes therein, a plurality of fingers adapted to successively pass through 120 125 130

the holes in the film and the first mentioned cylinder to lock the cylinder against rotation and to drop into the hole in the last mentioned cylinders to permit the rotation of the first mentioned cylinder and means for causing such rotation.

3. In an automatic road guide, the combination with a cylinder having a helical series of holes thereof, a plurality of fingers mounted above the cylinder, resilient means tending to move said fingers into said holes, a cylinder mounted within the first mentioned

cylinder and movable relative thereto and having a helical series of holes therein through which the fingers are adapted to extend and means for retracting the fingers immediately after their movement into the holes in the last mentioned cylinder.

In testimony whereof, I affix my signature, in the presence of two witnesses.

LLOYD E. SMALL.
